UNITED STATES PATENT OFFICE.

SPENCER C. CARY, OF BROOKLYN, NEW YORK, ASSIGNOR TO CARY MANUFACTURING CO., OF BROOKLYN, NEW YORK, A CORPORATION OF NEW YORK.

METALLIC FLOOR COVERING.

Application filed November 9, 1916, Serial No. 180,345. Renewed June 18, 1923.

To all whom it may concern:

Be it known that I, SPENCER C. CARY, a citizen of the United States, residing at the city of New York, borough of Brooklyn, county of Kings, and State of New York, have invented a certain new and useful Metallic Floor Covering, of which the following is a specification.

This invention is a floor covering composed of metal, the object in view being to provide a continuous marginal member adapted to impart a finished appearance to an edge portion of the metal covering.

The marginal member is characterized by a smooth external surface against which the foot or shoe may easily pass over without catching against said member. The member is of channeled form pressed and clamped upon the edge portion of the covering, said channeled member being interiorly stiffened by a stay member, preferably continuous. This stay member is fastened to the links of a row of units, and the end portions of the stay member are provided with means for closing the open ends of the channel in the marginal member, thus excluding to a substantial extent the admission of dirt, water or other substances from the interior of said channeled member.

Other functions and advantages of the invention will appear from the following detailed description taken in connection with the drawings, wherein—

Figure 1 is a plan view of a portion of the metal floor covering with my continuous marginal strip applied thereto.

Figure 2 is a vertical section on the line 2—2 of Figure 1.

Fig. 3 is a detail view in plan of the continuous stay member.

Fig. 4 is a detail view, on an enlarged scale, of a part of the stay member and a part of one of the links, illustrating more particularly the means for securing together said link and stay member.

Fig. 5 is a detail view, on an enlarged scale, of a part of the channeled member, a part of the stay member, and a part of one link, showing more particularly the manner of closing the open end of the channeled member.

The body of the floor covering is composed of units 10 assembled into rows, each row of units being held together by rods 11 which pass through suitable openings pro-

vided in the units of said row. It is preferred to employ units of the form shown in Figure 1, each unit consisting of complementary halves with inturned lugs, and the rods pass through openings in the halves of the units and through openings in the in-turned lugs thereof, but it will be understood that the invention is not restricted to the particular form of unit or the means for tying said units into rows. The units 65 cooperate with links 12, each link being positioned between the inturned lugs of the complementary members composing the unit. Said links are apertured for the rods 11 to pass through them, and thus the members 70 of the units in the row and the series of links employed in connection with said row are tied together by the rods 11. The links used in connection with rows positioned intermediate the marginal rows of the floor 75 covering are connected pivotally in the manner disclosed in certain prior patents granted to me, but in the case of the marginal row of units 1 employ links of the form shown in Figure 4 of the drawings. Each link is 80 reduced at an end portion to provide a prong 13 and shoulders 14, 15. The links used in connection with each marginal row of units are assembled and attached in the manner described and so that the shoulders 85 14 of said links are substantially flush with the units composing said marginal row, the prongs 13 extending a suitable distance from or beyond said units, and the shoulders 15 90 being positioned beyond the shoulders 14 and intermediate the units 10 and the prongs 13.

16 designates a stay member consisting preferably of a continuous metal rod or bar, the length of which is equal substantially to 95 the width of the floor covering, and the width of which is less than the thickness of the units 10. This bar or rod is provided intermediate its ends with apertures 17, and the prongs 13 are extended through the apertures of the bar or rod, after which the prongs are bent or turned over, as at 18, whereby the stay member 16 is attached rigidly to the links which serve as the means for connecting the continuous stay member 100 to the row of units. The bent ends 18 of the prongs force or clamp the continuous stay member 16 into contact with the shoulders 15 of the links, thus affording a solid bearing for the stay member relatively to the 105 110

marginal portion of the floor covering. The stay member is positioned lengthwise of the row of units and substantially centrally with respect to the depth of said units, thus leaving appreciable spaces or intervals between the top and bottom edges of the stay member and the corresponding top and bottom edges of the units 10, said stay member being spaced relatively to the units for a distance equivalent to the distance between the shoulders 14 15 of the links. The respective end portions of the stay member 16 are bent at right angles to the length of the stay member so as to form the closures 19, the contour of which corresponds substantially to the internal contour of the channeled marginal member 20, shown more particularly in Figures 1, 2 and 5 of the drawings.

The marginal member 20 is composed of a single piece of metal which is bent, folded or doubled upon itself so as to produce the channel 21, the edge portions of the metal composing the member 20 being in-turned to produce the flanges 22. In the manufacture of the channeled member 20 it is first blanked from a suitable piece of metal, the edges thereof are turned to form the flanges 22, and the metal blank is doubled upon itself to produce the internal channel. During the manufacture of the member 20 its form and dimensions are such that said member can be readily slipped over the stay member 16 for the purpose of having the desired contact with the links, the stay member and the units, whereby the channeled member encase the stay member and the end portions of the links, and said channeled member is substantially flush with the top and bottom members of the units, thereby imparting a desirable finish to the marginal portion of the metal floor covering. A characteristic feature of this invention consists in the use of a channeled marginal member, the exterior surface of which is smooth so as to preclude the floor covering from being caught in an object when taking up or laying down said floor covering, and to prevent the foot or shoe from catching against a roughened surface of the marginal member, the smooth exterior surface of said marginal member precluding the lodgment of dirt and other foreign matter upon the fabric.

The channeled marginal member is not attached or affixed by the use of separate devices to any part of the floor covering, but in the process of assembling the parts in the manufacture of said floor covering, the channeled member is compressed for the purpose of clamping it rigidly in position relatively to the stay member and the marginal row of units. As a further result of this clamping operation, the channeled member is compressed at its end portions so as to have engagement with the parts 19 of the stay,

whereby said parts 19 act as closures to the open ends of the channel in said marginal member.

In the manufacture of the floor covering the units, links and rods are assembled for the rods to tie the units and links together, the end portions of the rods being bent against the units at the end of the row. The stay member 16 is positioned over the prongs 13 of the links and into substantial contact with the shoulders 15, whereupon the prongs are bent against the outer surface of the stay member, thus rigidly attaching the latter to the links and the row of units. The marginal member 20 is now positioned so that it will slide over the stay member, the flanges 21 of said marginal member fitting into the spaces between the shoulders 14, 15 of the links. The channeled member is now slid lengthwise of the stay member and of the row of units, and when it is in position, the open ends of said channeled member are substantially closed by the end portions 19 of the stay member. At this stage in the manufacture of the covering, the channeled member is comparatively free or loose with reference to the units. The marginal portion of the floor covering is now placed within a press of suitable form, and is subjected to pressure, as a result of which the channeled member is compressed and clamped upon the stay member and the shouldered parts of the links. Another effect of the compressing operation is to clamp the end portions of channeled member upon the ends 19 of the stay member, so that the end portions of said channeled member are in close contact with the end portions 18 of the stay member, and it is to be noted, further, that the flanges of the channeled member are forced tightly into the spaces between the stay member and the row of units, the surfaces of the channeled member next to the units being substantially flush therewith.

Having thus fully described the invention, what I claim as new, and desire to secure by Letters Patent is:—

1. A metallic floor covering embodying units in rows, links attached to said units, each marginal link having shoulders and a prong, a stay member extending continuously with respect to the marginal row of units, said stay member being attached by the prongs to the links and being spaced with respect to the units, and a channeled marginal member encasing the stay member, said channeled member having flanges which by compression of the member are positioned to occupy the spaces between the units and the stay member.

2. A metal floor covering embodying rows of units, links connecting the units in adjacent rows, a channeled member coextensive in length with the units of a row, the end portions of said channeled member being

open, and a stay member in fixed relation to said channeled member and to the links of a marginal row of units, said stay member being provided with means extending outwardly therefrom and positioned in co-operative relation to the channeled member and closing the open end portions thereof.

3. A metal floor covering embodying rows of units, links connecting adjacent rows of units, the links at the marginal row of units being provided with tongues and with shoulders, a channeled member extending continuously with respect to the units of a row at a margin of said floor covering, and a stay member spaced from the units and extending continuously within the channeled member, said links at the marginal row of units being locked by upsetting the tongues into fixed relation to the stay member, and said stay member being in contact with the shoulders of the marginal series of links.

4. A metal floor covering embodying rows of units, links connecting adjacent rows of units, the links at the marginal row of units being provided with tongues and shoulders positioned one in rear of the other, a channeled member extending continuously with respect to the row of units at the margin of said floor covering, said channeled member being provided with inturned flanges which bound a longitudinal slot at the open side of said channeled member, and a stay member spaced from the units and extending continuously within said channeled member, said links at the marginal row of units and the continuous stay member being locked in fixed relation by upsetting the metal of the tongues against the stay member and the inturned flanges of the marginal member contacting with said stay member and with the shoulders of the links adjacent the marginal row of units.

5. A floor covering embodying units positioned in rows, links connecting said rows

of units, a continuous member at the margin of said floor covering, said continuous member being of channeled form in cross section and presenting a continuously closed outer edge and provided at the inner side with an opening, and a stay member substantially flat and positioned within said channeled member to contact with the top and bottom thereof, said stay member closing the open inner side of the channeled member, and said links being attached fixedly to said stay member.

6. A floor covering embodying units, links connecting said units, a continuous member of channeled cross section provided with a closed outer edge portion and with a longitudinal opening in the vertical face of the inner edge portion, a stay strip substantially flat and positioned within the channeled member in contact therewith, and closing the longitudinal opening in the inner side thereof, said links being fixedly attached to the stay strip and being free from direct attachment to the channeled member.

7. A floor covering embodying units positioned in rows, links connecting said rows of units, a continuous member of channeled cross section provided with inwardly extending longitudinal flanges, said continuous channel member presenting a continuously closed outer edge and providing an opening at the inner side which is partially closed by the inwardly extending flanges, and a stay member substantially flat and positioned within said channeled member to abut against the inner faces of the inwardly extending flanges to close said inner side of the channeled member, and said links being provided with tongues passing through said stay member and bent to fixedly attach the links to said member.

In testimony whereof, I have hereunto signed by name.

SPENCER C. CARY.
